UNITED STATES PATENT OFFICE

148,402

DESIGN FOR A LEAKPROOF CASE FOR A
CIGARETTE PACKAGE

Edward A. Abbatiello, Cincinnati, Ohio

Application April 26, 1946, Serial No. 128,966

Term of patent 14 years

(Cl. D85—2)

To all whom it may concern:

Be it known that I, Edward A. Abbatiello, a citizen of the United States and a resident of Cincinnati, in the county of Hamilton and State of Ohio, have invented a new, original, and ornamental Design for a Leakproof Case for a Cigarette Package, of which the following is a specification, reference being had to the accompanying drawings, which form a part thereof.

In the drawings:

Figure 4 is an end elevation and,

I claim:

The ornamental design for a leakproof case for a cigarette package, as shown.

EDWARD A. ABBATIELLO.
